UNITED STATES PATENT OFFICE

2,520,301

SHOE AND METHOD OF MAKING THE SAME

Fred L. Ayers, Waltham, Mass.

Application March 23, 1946, Serial No. 656,690

8 Claims. (Cl. 36—8.5)

1

This invention relates to shoes and to their manufacture and has for an object to produce a shoe, particularly of the stitch-down type, which is initially lasted by the slip lasting method.

A further object is to produce such a shoe having a counter stiffener incorporated therein.

Still another object is to produce such a shoe having a highly desirable interior heel contour.

For an understanding of these and other objects and advantages, reference may be had to the accompanying drawings in which:

Figure 1 is a top plan view of a combined innersole, inside backstay, and counter pocket or stiffener employed in the manufacture of a shoe in accordance with a preferred embodiment of this invention.

Figure 2 is a view partly in side elevation and partly in section of a partly completed shoe.

Figure 3 and 4 are cross-sectional views on lines 3—3 and 4—4, respectively, of Figure 2.

Figures 5 and 6 are views similar to portions of Figures 3 and 4, respectively, but showing the completed shoe.

Figure 7 is a view similar to Figure 6 but showing a shoe without the use of a separate counter stiffener, the counter pocket element serving alone for this purpose.

Referring to the drawings, at 1 is indicated an innersole having a rearward relatively narrow extension 2 which forms at least a portion of an inside backstay, this being in accordance with my application for patent Serial No. 628,168, filed November 13, 1945, which has now materialized into Patent No. 2,460,669, granted February 1, 1949. At the counter portion of the innersole it is provided with oppositely disposed lateral extensions 3 for a purpose which will later appear. Also, there is shown secured to the innersole and extending laterally thereof, a counter pocket or stiffening element 4. This element 4 may provide merely a pocket for the reception of a counter stiffener, or of itself it may have sufficient stiffness to perform this function without the use of an additional counter stiffener.

The shoe, in which this unit comprising the innersole and counter member is inserted, is provided with a lining only forwardly of the counter portion. This lining 5 is secured about its lower margin, as by stitching 6, to the margin of the innersole 1 forwardly of the extensions 3. The outer 7 of the upper remains unattached at its lower margin to the lining at this time. The inside backstay portion 2 is turned away from the sole member on the gradual curve shown at 8 in Figure 2 and is suitably secured to the heel por-

tion of the shoe upper, as shown in Figure 2. The marginal portions 10 of the counter pocket or stiffener forwardly of a pair of slots 11 at about the margin of the innersole are brought around and secured to the extensions 3 of the innersole, as shown in Figure 4, and if a separate counter stiffener is employed, such a stiffener also, preferably, has its lower margins out-turned and overlies the member 4 as shown at 15 in Figure 4. The stiffener is preferably one which is applied in limp condition and becomes hard thereafter, for example, a stiffener having a stiffening agent softenable by a solvent which later evaporates and causes the stiffener to rigidify. The shoe is then slip lasted, the innersole having been secured forwardly of the counter portion to the lining and at the counter portion to the counter stiffener or pocket.

After the slip lasting operation, the outer 7 is lasted, its free margins being turned outwardly as in stitch-down practice, and are secured to an outersole 20 as by stitches 21. In the forepart of the shoe the outer only has its outwardly turned margin attached to the outersole as shown in Figure 5. At the counter portion, however, not only is the margin of the outer turned outwardly, but it also overlies the counter pocket 4, and if a separate stiffener is used, this stiffener also, as at 15, and it also overlies the outturned extensions 3 of the innersole as shown in Figures 4 and 6. Figure 7 shows a construction similar to Figure 6, but without the use of a separate stiffener 15. All these outturned portions are secured together at the counter portion by the stitching 21, which forwardly of the counter portion, secures only the outer and out-sole together. The counter member 4, the stiffener, and the innersole may, if desired, be secured by a separate line of stitching 22 in addition to the stitches 21. This construction at the counter portion is of value in that it ties all the shoe parts, both of the sole and upper, together where the greatest stresses in service occur, while at the same time the forward portion of the upper is left relatively light and flexible.

After the parts are thus secured, the shoe is completed in any desired manner.

From the foregoing description of an embodiment of this invention it should be evident to those skilled in the art that various changes and modifications might be made without departing from its spirit or scope.

I claim:

1. The method of making a shoe, which comprises marginally securing an innersole to the lining of a shoe upper forwardly of the counter

portion, said innersole having lateral extensions at the sides of the counter portion, securing the lower marginal portion of a counter element to said lateral extensions of said innersole, slip lasting the shoe, and thereafter lasting the outer of the shoe upper and securing it to the margin of an outersole and at said counter portion securing it also to the lateral extensions of said innersole.

2. The method of making a shoe, which comprises marginally securing an innersole to the lining of a shoe upper forwardly of the counter portion, said innersole having lateral extensions at the sides of the counter portion, and a rearward extension constituting an inside backstay, securing a counter member to said backstay extension and the lower marginal portion of said counter member to said lateral extensions of said innersole, slip lasting the shoe, and thereafter lasting the outer of the shoe upper and securing it to the margin of an outersole and at said counter portion securing it also to the lateral extensions of said innersole.

3. A shoe having an upper provided with a lining in the forepart, an innersole secured about its forward margin to said lining and having lateral extensions at the sides of the counter portion, and a counter member having its lower margin secured to said innersole at said extensions, said upper having an outer portion enclosing said lining and counter member, and an outersole secured to said outer portion and free from securing to said lining in the forepart.

4. A shoe having an upper provided with a lining in the forepart, an innersole secured about its forward margin to said lining and having lateral extensions at the sides of its counter portion and a rearward extension forming an integral inside backstay, and a counter member carried by said innersole and rearward extension and secured at its lower margin to said innersole lateral extensions rearwardly of said lining, said upper having an outer portion enclosing said counter member and lining, and an outersole secured to said outer portion and at said counter to said innersole and free from securing to said lining in the forepart.

5. A shoe having an integral member comprising an innersole and inside backstay, a shoe upper secured to the marginal portion of said member and including an outer portion, a counter pocket

projecting laterally from the backstay portion of said member, and a counter stiffener between said pocket and outer portion.

6. A shoe having an integral member comprising an innersole and inside backstay, a shoe upper secured to the marginal portion of said member and including an outer portion, a counter pocket projecting laterally from the backstay portion of said member and adjacent to its lower margin being free from said backstay portion, and a counter stiffener between said pocket and outer portion.

7. A shoe having an integral member comprising an innersole and inside backstay, a shoe upper having a portion stitched to the marginal portion of said member and including an outer portion, a counter pocket projecting laterally from the backstay portion of said member and secured about its upper margin to said outer portion, and a counter stiffener between said pocket and outer portion.

8. A shoe having an integral member comprising an innersole and inside backstay, a shoe upper having a portion stitched to the marginal portion of said member and including an outer portion, a counter pocket projecting laterally from the backstay portion of said member and secured about its upper margin to said outer portion and adjacent to its lower margin free from said backstay portion, and a counter stiffener between said pocket and outer portion.
